UNITED STATES PATENT OFFICE.

DAVID E. MARSHALL, OF KANSAS CITY, MISSOURI.

APPARATUS FOR DISINTEGRATING SHAVINGS.

1,211,736.

Specification of Letters Patent.

Patented Jan. 9, 1917.

Application filed November 1, 1915. Serial No. 59,124.

To all whom it may concern:

Be it known that I, DAVID E. MARSHALL, a citizen of the United States, residing at Kansas City, in the county of Jackson and State of Missouri, have invented certain new and useful Improvements in Apparatus for Disintegrating Shavings, of which the following is a specification.

This invention relates to an apparatus for reducing wood waste to a fine granular form resembling sawdust.

In woodworking plants, furniture factories, planing mills, etc., vast quantities of waste are produced in the form of shavings, chips and small blocks. These forms of waste are commercially less valuable than sawdust; hence it is desirable and profitable to convert shavings, chips and small blocks into granular form, in which form it would be salable as packing material and for other purposes.

In order that my invention may be fully understood, reference will now be made to the accompanying two sheets of drawings, in which:

Figure 1 is a diagrammatic view in side elevation of an apparatus for the practice of the invention, certain parts being shown in section. Fig. 2 is an enlarged view in central vertical section of the preferred form of reducing hopper and vortex forming means, the latter being partly in elevation. Fig. 3 is a sectional plan view, taken on line III—III of Fig. 2. Fig. 4 is a sectional plan view of the vortex former, taken on line IV—IV of Fig. 2.

Referring to Fig. 1, the letter A designates a rotary blower or fan, of which 1 is the intake and 2, the discharge. 3 is a receiving trunk which is connected to the fan intake 1 and is provided with branches 4 into which the wood waste is deposited either by sweeping or otherwise. 5 is a branch tube and 6, a hopper at the upper end thereof, the function thereof being hereinafter described. Supported directly above the hopper 6 is a downwardly tapered cylindrical shell 7, in the bottom 8 of which is a small concentric tube 9, having open top and bottom. Secured within the tapered portion 7, is a reducing hopper B, which as shown comprises six plane walls 10 made of woven wire or other perforate metallic structure. Adjacent walls 10 are united or joined along their meeting edges by means of small bolts 11 which pass through holes in

flanges 12' of Y sectioned angle-bars 12. Said bars are supported by suitable knees or brackets 13 which are riveted to the shell 7 as shown at 14, Fig. 2. Walls 10 are herein- 60 after termed screens.

The lower part of shell 7 has an annular bottom 15 (Fig. 3) in which are two circular openings 29 in which are fitted the discharge spouts 16, 17. One spout, 17, is 65 offset sidewise, as shown at 18, to permit material to fall from tube 9 into hopper 6, and said spout is connected below the offset to the other spout 16, at 19.

Supported above the reducing hopper B, 70 is a vortex former C. In the construction shown, this comprises an outer drum 20, a hood 21 spaced above said drum 20 to leave an air opening 21^a, a tubular core 22, an annular head 23, and a blast tube 24 which 75 discharges a stream into the annular vortex chamber 25 in a tangential or non radial direction, through an opening 26. Tube 24 is connected by a tube 30, with the blower outlet 2.

Details: The drum 20 rests upon, or touches, the tops of the perforate walls 10, and has a flange 27 that meets the top of the tapered drum 7. The hood 21 is mounted on lugs 28. The core 22 is supported by the annular head 23, as by soldering. The parts shown by Fig. 2 may be supported in any suitable manner, either from joists or from the floor.

The apparatus having now been fully described, the manner in which the same is to be employed is as follows. The blower A being put in motion and driven at high velocity by a motor (not shown) said blower will induce a current of air through each 95 branch 4 and trunk 3, through the blower, thence through tubes 30 and 24, into the vortex chamber 25, where it takes a rotary and descending, spiral motion. Passing into the hopper B and through its screens 10 the air 100 maintains the descending, spiral motion, and escapes through spouts 16, 17. Air will also be drawn into the core tube 22 beneath the hood 21. And air will also be sucked into receiving hopper 6 and tube 5. When the 105 raw material (consisting of, say, shavings, chips, blocks and sawdust) is fed into a branch 4, it is swept along through tube 3, blower A, tubes 30, 24, into chamber 25, where it forms a descending vortex having 110 high velocity. By gravity and air pressure the pieces of wood are carried slowly

- downward, and by centrifugal force they are dashed violently upon the angularly disposed screens 10, whose flatness augments the force of the impacts. By this means the shavings and the solid pieces are cut, broken and abraded, thereby forming "sawdust" which passes into the receiver 7 and spouts 16, 17, being discharged by spout 16 at 31.
- 10 The material will not all be reduced to "sawdust" by one passage through the apparatus, and obviously the portion which does not pass through the screen perforations will descend through tube 9 and be blown into hopper 6, whence it will be conveyed by the air stream through tube 5 into the blower, thence back to the vortex former and reducing hopper where it will be again subjected to the aforesaid cutting, abrading, and 15 breaking action upon the screens 10. This operation is repeated endlessly, and thus the coarse material will be continuously reduced to a granular form as received through the discharge spout 16.
- 20 The wire of which the screens 10 are woven may be of square or other noncircular section, but round wire has been found operative.
- 25 Having thus described my invention, what I claim and desire to secure by Letters Patent, is:
- 30 1. In combination, a receptacle comprising a plurality of angularly disposed inclined perforated walls, and pneumatic means for driving a vertical stream of wood waste into said receptacle and against said walls.
- 35 2. In combination, a receptacle comprising a plurality of angularly disposed inclined perforated walls, and pneumatic
- 40
- means for maintaining a descending vortex of air laden with wood waste, within said receptacle.
3. In combination, a receiving trunk, a delivery trunk, a rotary blower connected between said trunks, a drum having a vertical axis, said delivery trunk being connected non-radially to said drum, a pneumatic wood reducing hopper below and communicating with said drum, said hopper having an open bottom for eduction of unreduced material, a receptacle spaced below said open bottom to receive the unreduced material, and a spout from said receptacle to said receiving trunk.
4. In combination, a receiving trunk, a delivery trunk, means for circulating air through said trunks at high velocity, a drum having a vertical axis and with which the delivery trunk is connected on a tangent, a pneumatic wood reducing hopper below and communicating with said trunk and embodying angularly disposed screens, said hopper having an open bottom for eduction of unreduced material, a receptacle spaced below said open bottom to receive the unreduced material, a spout leading from said receptacle to the receiving trunk, a conical shell surrounding the wood reducing hopper to receive the reduced material therefrom, and two communicating spouts leading from the bottom of said shell to conduct the reduced material therefrom.
- 55
- 60
- 65
- 70
- In testimony whereof I affix my signature, in the presence of two witnesses.
- DAVID E. MARSHALL.
